UNITED STATES PATENT OFFICE

ARTHUR RONALD TRIST, OF LONDON, ENGLAND, ASSIGNOR, BY MESNE ASSIGNMENTS,
TO PANTONE CORPORATION, OF NEW YORK, N. Y., A CORPORATION OF DELAWARE

SCREEN FOR PHOTOGRAPHIC PURPOSES, PHOTOMECHANICAL PRINTING PROCESSES
AND THE LIKE

Application filed October 28, 1927, Serial No. 229,314, and in Great Britain November 4, 1926.

This invention relates to improvements in the manufacture of screens for photographic purposes, photomechanical printing processes and the like said screens being of the 5 type in which the changes in opacity of the different parts are gradual and has for its object the provision of means whereby greater and more reliable control in the gradation of the change of opacity is available thus 10 enabling more accurate gradation of the tones of a picture and a more faithful reproduction of the picture to be obtained than has been possible heretofore.

This invention consists in the arrangement 15 of a light tight chamber; a half tone or ruled screen in half tone relation to a film of photographically sensitive material arranged behind said screen in said chamber; an aperture in said chamber in half tone relation to 20 said screen, said aperture being similar in shape to the shape of the openings formed by the rulings of the screen employed; a rotatable diaphragm associated with said aperture, the opaque part of said diaphragm 25 being of such shape that it will when rotated give a predetermined rate of change of opacity in the multiple images thereof on the sensitive material; a source of illumination and means for continuously rotating said 30 diaphragm to produce a screen having shaded areas.

In the drawings:—

Figure 1 illustrates a portion of a screen having a positive image formed according to 35 this invention and drawn to an enlarged scale;

Figure 2 is a detail view of a rotatable diaphragm employed in the manufacture of the screen illustrated in Figure 1;

Figure 3 illustrates a portion of a screen having a negative image formed according to this invention and drawn to an enlarged scale;

Figure 4 is a detail view of a rotatable diaphragm employed in the manufacture of the screen illustrated in Figure 3;

Figure 5 illustrates in elevation one form of apparatus for producing the screens illustrated in Figures 1 and 3;

Figure 6 is a transverse section of a mount

suitable for use in the arrangement illustrated in Figure 5;

Figure 7 is a front elevation of the carrier for the rotatable diaphragm; and

Fig. 8 diagrammatically illustrates the 55 arrangement of the various parts during the photographing step in the manufacture of the improved screen.

In Figure 1 of the drawings, *a a* are comparatively small areas, which, for the sake 60 of simplicity are illustrated as of square shape, said areas being contiguously arranged upon one surface of a transparent base *b*, in such number as to cover the whole surface of *b*.

It will be seen that, as is usual in screens having shaded areas, the photographic density of each of the small areas *a* varies from substantial photographic transparency at one part *c* to substantial photographic 70 opacity at the other part *d*.

In Figure 1 the photographically transparent part *c* is located at the centre of each area *a* whilst in Figure 3 the transparent part *c* is at the margin of each area *a*.

The rate of change of density from centre *c* to border *d* of each of the areas *a* has to be adjusted so that the tones of the printed reproduction bear a definite relationship to the tones of the picture reproduced.

In Figure 3 of the drawings, *a¹ a¹* are comparatively small areas comparable with areas *a a* of Figure 1, said areas being, for the sake of simplicity, illustrated as of square shape. The areas *a¹ a¹* are contiguously arranged upon one surface of a transparent base *b¹* in such number as to cover completely the whole surface of *b¹*.

As arranged in Figure 3, the photographic density of each of the small areas *a¹* varies 90 from substantially photographic opacity at the centre *d¹* to substantially photographic transparency at the outer part *c¹*.

Although the contiguously arranged areas *a* have been illustrated in Figures 1 and 3 as 95 of square shape, such areas may be of any geometrically similar shape provided that the whole of the surface of the base *b* can be covered with such areas.

In the production of a screen by means of 100

the invention and having square areas a ruled half tone or any similar screen having a line to space ratio of 1:1 may be used as hereinafter explained.

5 Careful experiment has shown that by means of a rotating diaphragm it is possible to exercise that control of density gradation which is essential to success.

Figure 5 shows apparatus suitable for producing a screen of the type illustrated in Figures 1 and 3 and Figures 2, 4, 6 and 7 illustrate the operative elements in detail. In Figures 5 and 6 a frame *e* is formed integrally with a mount *f* and attached to the front board *g* of the light tight chamber, said frame *e* being provided with bearings *h* and a spindle *i* carrying a friction roller *j* and a driving pulley *k*.

A carrier *l* is adapted to be located within the frame *e* said carrier having a rotatable part *m* which is mounted upon rings of balls *n* and *n*¹ in order that the said part *m* may rotate with the minimum of friction and vibration. The part *m* has an aperture *o* and a seating *p* within which a diaphragm *p*¹ (such as that illustrated in Figure 2) may be disposed, said diaphragm *p*¹ being maintained in place in the seating *p* by means of suitable spring clips, not shown.

30 The carrier *l* is also provided with a non-rotatable diaphragm *q* having an aperture *r* geometrically similar in shape with the shape of the areas, for example, if the boundary of each of the small areas is to be in the shape of a square, as illustrated in Figure 1, then the aperture *r* will be square in shape.

The part *m* is provided with a grooved edge for engagement with the friction roller *j* which is rotated from any suitable source of motion; as illustrated in Figure 5 a clockwork motor *s* having a pulley *t* transmits motion to the pulley *k* by means of the belt *u*.

40 The diaphragm *p*¹ as illustrated in Figure 2 is formed of transparent material the patch *v* comprising a plurality of portions of circumferential bands, zones or areas, the circumferential length of each band or the like being adjusted to suit the desired rate of change of density across each of the areas *a* of Figure 1.

45 The diaphragm *p*² as illustrated in Figure 4 is formed of opaque material and has an aperture *r*¹ therein shaped to produce the shaded areas *a*¹ of Figure 3, that is to say, if the rate of change of density across each area *a*¹ of Figure 3 is similar to the rate of change of density across each area *a* of Figure 1 then the aperture *r*¹ in the diaphragm *p*² will be similarly shaped to the patch *v* in the diaphragm *p*¹.

50 During the preparation of a screen with the improved apparatus a ruled or half tone screen *w* having a line space ratio of 1:1 is so disposed in the light tight chamber *x* in relation to a glass dry plate *y* or strip-

50 pable film of light sensitive material mounted upon a rigid, semi-rigid or flexible base that the surface *z* of said light sensitive material is covered by the multiple image of the aperture *r* as illustrated in Figure 8.

A source of light *L*, *L* for illumination purposes is arranged in the ordinary way adopted with half tone work and the diaphragm *p*¹ or *p*² as the case may be is continuously rotated by the motor *s* in manner already described, a time exposure resulting in a blurred multiple image being photographically effected of the rotating patch *v* or aperture *v*¹ as the case may be in the light sensitive material.

55 Upon completion of the exposure the image is developed in the ordinary way and if the patch *v* has been used said image will resemble the representation shown in Figure 1 or if an aperture *v*¹ has been used said image will resemble the representation shown in Figure 3 the proportions in either case being defined by the line screen used during exposure and the variation in relative density of each small area being dependent 60 upon the shape of the patch *v* or the aperture *v*¹.

65 To control the rate of change of density across each of the areas *a* or *a*¹ the circumferential bands of *p*¹ or *p*² are varied in accordance with results obtained. For instance if a regular rate of change is required a basic chart is prepared having say twenty-five spaces; one of said spaces is pure white and one of said spaces is intense black the remaining spaces being grey tones of such different and intermediate values that the chart represents twenty-four progressive tone steps. Such a chart is photographed through the improved screen and the resultant dot image is examined and the dots in different parts of the chart representation measured so as to see if the change in dot area in the printed result will be comparable with the change in tone of the basic chart any inaccuracies being corrected by extending or reducing the length of one or other of the circumferential bands.

70 In use such a screen as illustrated in Figure 1, may be supported by a film of celluloid or the like about five or ten one ten thousandths part of an inch in thickness said film and screen being interposed between and in close contact with the continuous tone negative transparency of the picture to be reproduced and a sheet of metal or other material having a photographically sensitive coating thereon, the actual screen surface being in contact with the photographically sensitive coating. After exposure to light, the metal plate is suitably treated and forms a printing plate with an image composed of sharply defined dots the size of each of which is dependent upon the value of the tone at that particular part of the picture.

In some cases in order to facilitate the handling of the screen when mounted on the film of celluloid the flexible screen as a whole may be mounted in a frame or other device 5 adapted to hold the said screen perfectly flat.

photographic transparency at one part of the area to relative photographic opacity at another part of the area.

ARTHUR RONALD TRIST. 70

I claim:—

1. Improved means for producing screens of the type specified comprising a light tight chamber; a half tone or ruled screen in half tone relation to a film of photographically sensitive material arranged behind said screen in said chamber; a fixed diaphragm in said chamber having an aperture in half tone relation to said screen, said aperture being similar in shape to the shape of the openings formed by the rulings of the screen employed; a rotatable diaphragm associated with said aperture, the opaque part of said diaphragm being of such shape as will give a predetermined rate of change of opacity in the images thereof on the sensitive material; a source of illumination and means for continuously rotating said diaphragm.

2. Improved means for producing screens of the type specified as claimed in claim 1, characterized by that the opaque part of the rotatable diaphragm is composed of a plurality of circumferential bands, the circumferential length of each of which is such as will give the desired rate of change of density across each of the areas projected on to the photographically sensitive material.

3. A method of producing a photographic screen which comprises converting a substantially uniform beam of light into a beam wherein the intensity varies progressively across its area, thereafter resolving said beam into a plurality of similar beams and projecting said beams upon a light sensitive medium.

4. Apparatus for producing a photographic screen comprising means for providing a beam of light, means for varying the intensity of said beam progressively across its area and means for resolving said beam into a plurality of similar beams, all of said beams being positioned for effecting the projection of said beams upon a light sensitive medium.

5. Apparatus for producing a photographic screen comprising means for providing a beam of light, a diaphragm adapted for varying the intensity of said beam progressively from its center to its circumference and a screen adapted for resolving said beam into a plurality of similar beams, all of said elements being positioned for effecting the projection of said beams upon a light sensitive medium.

6. A screen for photographic purposes, photomechanical printing processes and the like, comprising a translucent sheet provided with a plurality of relatively small contiguous areas, the density of each of which uniformly and continuously varies from relative
